CLAIM

The ornamental design for a two compartment heavy duty rectangular container, as shown and described.

DESCRIPTION

FIG. 1 is a perspective view of a two compartment heavy duty rectangular container showing the new design.

FIG. 2 is another perspective view of the two compartment heavy duty rectangular container of FIG. 1.

FIG. 3 is a front view of the two compartment heavy duty rectangular container of FIG. 1.

FIG. 4 is a rear view of the two compartment heavy duty rectangular container of FIG. 1.

FIG. 5 is a side view of the two compartment heavy duty rectangular container of FIG. 1.

FIG. 6 is an opposite side view of the two compartment heavy duty rectangular container of FIG. 1.

FIG. 7 is a top view of the two compartment heavy duty rectangular container of FIG. 1; and,

FIG. 8 is a bottom view of the two compartment heavy duty rectangular container of FIG. 1.

Broken lines show environmental structure that forms no part of the claimed design.
